UNITED STATES PATENT OFFICE.

KENNETH ELMER FIFE, OF TORONTO, ONTARIO, CANADA.

OIL FILTER.

Application filed June 27, 1927. Serial No. 201,793.

My invention relates to improvements in oil filters, and the object of the invention is to devise a simple construction of filter which may be applied directly in an oil line connecting the discharge with the intake so that the used oil may be automatically filtered and returned for re-use and to devise such a filter which will effectively remove all sediment from the oil resulting in providing clear oil adapted for re-use, and it consists essentially of the arrangement and construction of parts as hereinafter more particularly explained.

Fig. 1 is a perspective view of my filter partially broken away in section to exhibit the interior construction thereof.

Fig. 2 is a transverse sectional view taken through the centre of the main inlet pipe.

Fig. 3 is a sectional view taken through Figure 2, on line 3—3.

In the drawing like characters of reference indicate corresponding parts in each figure.

1 indicates an outer casing forming a container for my filtering device. The upper edge of the open top of the container is provided with a surrounding flange 1^x provided with a cover plate 1° which is suitably bolted to the flange 1^x provided with intermediate packing 2.

3 is the main inlet pipe provided with an annular flange 3^x located within the container and between which and the cover plate 1° fits a packing washer 3°. 4 is the outlet pipe leading from the container to a suitable point of return for re-use in the engine of the automobile. 5 is an enlargement which is formed integral with the main inlet pipe 3, the orifice of the pipe 3 being extended through the enlargement 5 as clearly indicated in Figure 2.

The enlargement 5 is provided with laterally extending tubular portions 6 and 7, the portion 6 having a closed end 6^x and the end of the portion 7 with a valve seat 7^x with which a relief valve 7° coacts, such valve being enclosed in the casing 8 which is screwed onto the end of the extension 7. 9 is the central feed pipe located on a line with the main inlet pipe 3 and 10 and 11 are supplemental feed pipes extending from the outer ends of the tubular portions 6 and 7. 12 and 13 and 14 are open metallic frames which are preferably rectangular and provided with orifices 12^x, 13^x and 14^x into which the feed pipes 9, 10 and 11 extend so

as to feed the oil in the open centre of the frames 12, 13 and 14. 12° and 12¹ are sheets of filtering material which are laid over the open faces of the frame 12 at each side thereof. 13° and 13¹ and 14° and 14¹ are similar sheets of filtering material which are laid over the open faces of the corresponding frames 13 and 14.

In order to hold the adjacent sheets of filtering material apart, such as at 13° and 12° I insert a sheet of perforated material preferably woven wire such as indicated at 16 so as to provide for a discharge passage for the oil forced through the filtering material to pass into the container 1.

In order to prevent the mesh of the wire being forced into the substance of the filtering material I provide spacing pieces 17 and 18 which fit between each side of the woven wire mesh 16 and that portion of the filtering material extending around the frames 12 and 13.

19 and 20 are end plates which bear against the outermost perforated sheets 16^x and 16°. The end plates 19 and 20 are provided with lugs 19^x and 20^x at suitable positions through which tie bolts 21 extend so as to draw the plates together and tie the frames, interposed filtering material 16 and perforated sheets into a compact body which rests on the bottom of the container 1.

The oil is pumped from the engine through the main inlet pipe 3 into the feed pipes 9, 10 and 11 and into the open frames 12, 13 and 14. The oil is then forced laterally by the pressure through the filtering material into the perforated sheet 16 which permits it to drain downwardly into the container 1 so as to be discharged through the discharge pipe 4 to be conveyed to the point for re-use.

From this description it will be seen that I have devised a very simple device which may be applied directly to the oil feed of an automobile engine so as to be permanently carried therewith and which automatically functions to filter or strain the oil immediately it is discharged so as to return it for re-use, and at the same time provide a filter which is simple in construction, compact in form and which will thoroughly filter or strain the oil passing therethrough.

It may be further pointed out that in filters which have been hitherto used the filtering material when saturated with dirt and other foreign matter removed from the oil

is destroyed together with the containing apparatus, involving a great deal of unnecessary expense in renewing the filters. Whereas in my device when the frames, 12, 13 and 5 14 become filled so that the oil will not properly filter the apparatus may be easily opened the frame removed and cleaned and new filtering material inserted, involving a comparatively very slight expense.

10. What I claim as my invention is:—

A filtering device comprising imperforated end plates, a series of open frames or

15 rims arranged parallel in closely adjacent position and having an oil inlet extending through the upper portion of the frame, between the end plates, a filter sheet extending through each opposing face of each frame, a woven screen extending between each pair of filter sheets and extending between the frames of the outer periphery thereof and thereby forming a peripheral outlet to discharge the oil. 20
